UNITED STATES PATENT OFFICE.

ALFRED M. REMINGTON, OF FITCHBURG, MASSACHUSETTS, ASSIGNOR TO SIMONDS MANUFACTURING COMPANY, OF FITCHBURG, MASSACHUSETTS, A CORPORATION OF MASSACHUSETTS.

HACK SAW.

1,424,378.

Specification of Letters Patent. Patented Aug. 1, 1922.

Application filed April 16, 1921. Serial No. 461,776.

To all whom it may concern:

Be it known that I, ALFRED M. REMINGTON, a citizen of the United States of America, and resident of Fitchburg, in the county 5 of Worcester and State of Massachusetts, have invented new and useful Improvements in Hack Saws, of which the following is a specification.

The objects of the invention are to provide 10 a hack-saw which has few parts, which is simple and economical in construction, which is rigid and durable in use, which is readily adjustable to blades of different lengths, in which a blade may be quickly and easily 15 mounted and tensioned, which has no thumb-nut at the end of the frame, which is stiff and compact, and which is non-collapsible when the blade breaks.

Instead of using auxiliary tensioning 20 means at the junction of the blade with one of the blade-supporting arms, involving additional parts which add to the cost of manufacture and to the difficulty of operation, the present invention contemplates a 25 unique interconnection between one of the blade-supporting arms and the longitudinal frame bar by virtue of which the arm may be moved relatively to the bar not only to tension the blade but also to adjust for 30 blades of different lengths. Thus instead of requiring two adjusting means, one between the arm and bar to adjust for blades of different lengths and one between the arm and blade to tension the blade, the present invention 35 provides a single adjusting means adapted to serve both purposes.

The tensioning movement of the arm relatively to the bar is preferably effected by means of a screw interengaging between the 40 frame and arm and this movement is preferably a swinging movement. This may be accomplished by providing the arm with two bearings spaced longitudinally of the bar, one bearing engaging the side of the 45 bar next to the blade and the other bearing engaging the opposite side of the bar, and one bearing comprising a screw or other adjustable device whereby the arm may be swung about the other bearing as a pivot. 50 The bearings on said opposite sides of the bar may be provided by making a recess in the arm to receive the bar so that the arm surrounds the bar on at least three sides (top, bottom and one side), but the recess 55 is preferably in the form of an opening ex-

tending through the arm so that the bar is entirely surrounded.

In order to space said bearings farther apart along the bar, and thereby increase the leverage of the tensioning adjustment, 60 the arm is preferably provided with a head having bearing portions extending forwardly and rearwardly, respectively, from the arm along the bar.

The two bearings may be variously located relatively to the arm and bar, so long as they are separated longitudinally of the bar, but they are preferably located forwardly and rearwardly, respectively, of the center line of the arm, with the forward 70 bearing inside the bar and the rearward bearing outside the bar. By making the inside bearing the adjustable bearing it does not project outside the outline of the frame, but I prefer to make the outside bearing the 75 adjustable one inasmuch as it is more accessible for adjustment.

In order to restrain the adjustable arm against displacement longitudinally of the bar after it has been properly positioned 80 for the length of the blade to be used, one of the bearings, preferably the non-adjustable bearing, is arranged to interengage with the bar as for example by means of a tongue and groove interengagement, the tongue 85 preferably being on the arm and the groove on the bar.

One of the frame arms may be used as a handle but when the adjustable arm is provided with a head the head preferably has a 90 handle extending therefrom in spaced relationship to the arm.

In order more clearly to illustrate the nature of the invention I have illustrated one embodiment thereof in the accompanying 95 drawings, in which,

Fig. 1 is a side elevation of a hack-saw frame with a blade mounted therein;

Fig. 2 is a similar view with the blade removed;

Fig. 3 is a vertical transverse section on the line 3—3 of Fig. 1; and

Fig. 4 is a vertical longitudinal section of the rear portion or body of the frame.

The particular embodiment of the invention illustrated in the drawings comprises a longitudinal bar 1 extending the full length of the blade and somewhat beyond the rear end of the blade, and two transverse arms 2 and 3 to which the blade 4 is adapted to 105 110

be attached by means of pins 5 and 6 extending laterally from the arms 2 and 3. The arm 3 is provided with a head having forwardly and rearwardly extending portions 7 and 8 respectively. The head is provided with an opening 9 to receive the bar 1, this opening being in the form of a channel open at the top except at the rear end where the top is closed by a bridge 10. The under surface of the bridge 10 is preferably inclined so as to seat squarely against the upper side of the bar 1 in the position of the parts shown in Fig. 2. A set screw 11 is threaded through this bridge to engage the upper side of the bar 1. The forward portion 7 of the head is provided with a tongue 12 adapted to fit into any one of the grooves 13 in the lower side of the bar 1; and the rearward portion 8 of the head is provided, in the bottom of the recess 9, with a stop 13^a adapted to seat against the lower side of the bar 1. The rear end 8 of the head is provided with a dependent handle 14 by which the saw may be operated.

In placing a blade in the frame the set screw 11 is threaded out to the position shown in Fig. 2 whereupon the body, comprising arm 3, head 7—8 and handle 14, swings into the position shown in Fig. 2. The body may then be adjusted longitudinally of the bar until the tongue 12 seats in the particular groove 13 which affords the proper spacing between the pins 5 and 6 to suit the blade 4 to be used, whereupon the blade is hooked over the pins 5 and 6. By threading the set screw 11 downwardly through the bridge 10 against the upper side of the bar 1, the body of the frame is swung in a counter-clockwise direction about the tongue-and-groove interengagement until the stop 13^a seats against the bottom of the bar 1 or until the blade is properly tensioned.

From the foregoing it will be evident that my improved hack-saw frame involves only three parts and is simple and economical in construction. By virtue of the long head 7—8 fitting around the bar 1 and the spaced bearings at the tongue 12 and set-screw 11 respectively, the frame is very stiff and rigid in use. The frame is readily adjustable to blades of different lengths by merely sliding the body of the frame along the bar 1; and the blade may be quickly and easily mounted and tensioned by the set-screw 11 located in a position which is convenient and which does not interfere with the use of the saw. With the stop 13^a bearing against the bottom of the bar 1, or even if it is slightly spaced from the bar, the frame will not collapse when the blade breaks. Indeed, the frame would be non-collapsible without the stop 13^a, the body merely being slidable on the bar 1 when a blade breaks. Thus the single screw 11

serves both to tension the blade and also to lock the adjustable arm 3 to the frame 1.

I claim:

1. A hack-saw frame comprising a bar extending substantially the full length of 70 the blade and having at one end thereof a lateral arm adapted to support one end of the blade, a second arm pivotally mounted on said bar to support the other end of the blade, means for swinging the second arm 75 on the bar to tension the blade, and means positively to hold said arm substantially in normal position independently of the tension of the blade.

2. A hack-saw frame comprising a longitudinal bar and a transverse blade-supporting arm adjustable thereon, the arm having a recess therein to receive the bar and having three bearings spaced longitudinally 80 of the bar to engage the bar on the side 85 next to the blade and on the opposite side respectively, one bearing interfitting with the bar to restrain displacement of the arm lengthwise of the bar, one other bearing being adjustable to swing the arm in the plane 90 of the blade, and the three bearings being correlated to hold the arm substantially in normal position independently of the tension of the blade.

3. A hack-saw frame comprising a longitudinal bar and a transverse blade-supporting arm adjustable thereon, the arm having a recess therein to receive the bar and having three bearings spaced longitudinally of 100 the bar in said recess to engage the bar on the side next to the blade and on the opposite side respectively, the bar and one of said bearings having a transverse tongue-and-groove interengagement, and another bearing comprising a screw adjustable to 105 swing the arm about said transverse tongue-and-groove interengagement, and the other bearing being correlated with the first two bearings to hold the arm substantially in 110 normal position independently of the blade.

4. A hack-saw frame comprising a longitudinal bar and a blade-tensioning arm adjustable thereon, said arm having a head provided with forward and rearward portions extending along said bar in both directions from the arm, said head having an opening to receive said bar therethrough, said bar having bearing surfaces facing toward and from the blade respectively, said rearward and forward portions of the head having bearings engaging said bearing surfaces respectively, one of said bearings being adjustable to swing said head about the other bearing.

5. A hack-saw frame comprising a longitudinal bar and a blade-tensioning arm adjustable thereon, said arm having a head provided with forward and rearward portions extending along said bar in both directions from the arm, said head having an 125

130

opening to receive said bar therethrough, said bar having bearing surfaces facing toward and from the blade respectively, said rearward and forward portions of the head 5 having bearings engaging said bearing surfaces respectively, one of said bearings being adjustable to swing said head about the other bearing, and said head having a handle extending therefrom in spaced relationship to said arm.

6. A hack saw frame comprising a longitudinal bar, a transverse blade-supporting

arm on said bar, said arm having an elongate portion recessed to receive said bar and having a bridge spanning the recess, a screw 15 threaded through said bridge to engage said bar whereby said arm is caused to swing upon one end of said elongate portion as a pivot for tensioning the blade, and a handle on said elongate portion for operating the frame.

Signed by me at Fitchburg, Massachusetts, this eighth day of April, 1921.

ALFRED M. REMINGTON.
